UNITED STATES PATENT OFFICE.

ROBERT W. SCOTT, OF LEEDS POINT, NEW JERSEY, ASSIGNOR OF ONE-HALF
TO LOUIS N. D. WILLIAMS, OF OGONTZ, PENNSYLVANIA.

RIBBED KNITTED FABRIC.

No. 846,428.

Specification of Letters Patent.

Patented March 5, 1907.

Application filed June 25, 1906. Serial No. 323,266.

To all whom it may concern:

Be it known that I, ROBERT W. SCOTT, a citizen of the United States, residing in Leeds Point, Atlantic county, New Jersey, have invented certain Improvements in Ribbed Knitted Fabrics, of which the following is a specification.

My invention relates to that class of knitted fabrics in which ornamental open-work effects are produced by the formation of eyelet-holes in the knitted web, the object of my invention being to produce such ornamental or open-work effects in ribbed webs.

In the accompanying drawing, Figure 1 is an exaggerated view of a piece of ribbed knitted web, illustrating the manner of forming eyelet-holes therein in accordance with my invention; and Fig. 2 is likewise an exaggerated view illustrating the arrangement and manipulation of the needle of a knitting-machine whereby such eyelet-holes are produced.

Referring, in the first instance, to Fig. 1 of the drawing, *a* and *a'* represent the face-wales of the fabric, such as are produced upon the cylinder-needles of a rib-knitting machine, and *b* and *b'* represent the rib-wales, such as are produced upon the dial-needles of the machine. In order to produce an eyelet-hole in the ribbed web—such, for instance, as represented at *c*—a stitch of a wale *b* is transferred from a dial-needle onto an adjoining cylinder-needle of the machine and is then cast off from said dial-needle, and in knitting the next course an open loop *d* is drawn upon the dial-needle in order to again start the rib-wale *b*.

The disposition and manipulation of the needles for effecting the operation described will be understood on reference to Fig. 2, in which *a'* represent cylinder-needles for producing the face-wales *a* of the fabric, and *b'* represent the dial-needles for producing the rib-wales *b*. In knitting the web both sets of needles are in action, as shown, and when it is desired to form an eyelet-hole *c* a rib-needle is projected and then shogged laterally so as to bring the stitch thereon into the plane of the adjoining cylinder-needle *a'*, which is then projected so as to enter said stitch, whereupon the needle *b'* is retracted in order to cast the stitch therefrom and onto the cylinder-needle, and is then restored to its normal position in order to draw a fresh loop *d* in the formation of the next course of the web.

So far as I am aware I am the first to produce a ribbed web having ornamental or open-work effects produced therein by transferring stitches from wales of one face of the web to adjoining wales of the other face. In carrying out my invention I can use a machine equipped with ordinary latch-needles, and I effect the transfer of the stitches from needles of one set to those of the other set by simple movements of the needles themselves, as in my Patent No. 834,763, dated October 30, 1906, without the aid of supplementary transfer mechanism.

I claim—

1. A ribbed knitted web having eyelet-holes therein produced by transfer of a stitch of a wale of one face into an adjoining wale of the other face.

2. A ribbed knitted web having eyelet-holes therein produced by transfer of a stitch of a wale of one face into an adjoining wale of the other face, said transferred stitch being followed by an open loop in the wale from which the transfer was made.

3. The mode herein described of producing eyelet-holes in ribbed knitted webs, consisting in knitting the web upon two sets of needles drawn in different directions in adjacent wales, and then transferring stitches from wales drawn in one direction to interloop with wales drawn in the other direction.

4. The mode herein described of producing eyelet-holes in ribbed knitted webs, consisting in knitting the web upon two sets of needles drawing in different directions in adjacent wales, and then transferring stitches from wales drawn in one direction to interloop with wales drawn in the other direction, solely by movement of the needles in respect to one another.

5. The mode herein described of producing eyelet-holes in ribbed knitted webs, consisting in knitting the web upon two sets of needles drawn in different directions in adjacent wales, and then transferring stitches from wales drawn in one direction to interloop with wales drawn in the other direction, solely by movement of the needles in respect to one another, and then knitting further courses of web by normal operation of the needles.

6. The mode herein described of producing eyelet-holes in ribbed knitted webs, consisting in knitting the web upon two sets of needles drawn in different directions in adjacent

wales, and then transferring stitches from wales drawn in one direction to interloop with wales drawn in the other direction, solely by movement of the needles in respect 5 to one another, and then knitting further courses of web by normal operation of the needles.

In testimony whereof I have signed my name to this specification in the presence of two subscribing witnesses.

ROBERT W. SCOTT.
